ATTORNEY.

Patented June 9, 1925.

UNITED STATES PATENT OFFICE.

MORRIS FOLKMAN, OF CLEVELAND, OHIO, ASSIGNOR OF ONE-HALF TO JOSEPH FOLKMAN, OF CLEVELAND, OHIO.

BADGE FASTENER.

Application filed August 22, 1924. Serial No. 733,562.

To all whom it may concern:

Be it known that I, MORRIS FOLKMAN, a citizen of the United States, residing at Cleveland, in the county of Cuyahoga and State of Ohio, have invented certain new and useful Improvements in Badge Fasteners, of which the following is a specification.

This invention relates to improvements in badge fasteners, the primary object being to provide a simple and inexpensively constructed device which will reliably retain a badge or the like upon an article of wearing apparel.

Another object is to provide a fastener of this character in which the locking bar or bodkin serves the double function of guiding the fastener through a button hole or the like, and thereafter serving to retain the fastener in the button hole.

It is likewise an object of this invention to provide a fastener including a pivoted pawl which co-acts with other members to frictionally retain the locking bar in operative position.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Figure 1 is a side elevation of a badge provided with a fastener constructed in accordance with my invention, the parts being shown in locked position;

Figure 2 is a central vertical sectional view, the locking bar being shown in unlocked position;

Figure 3 is a rear elevation of the device as shown in Figure 1, and

Figure 4 is a detail perspective view of the fastener.

Having more particular reference to the drawings throughout which similar characters of reference designate similar parts, this improved badge fastener may be stated as comprising a channeled body portion 5 which may be welded or otherwise secured to the back of a badge B. The free or outer end of the body portion is substantially inverted U shape, thereby providing an opening or slot 6 through which the bodkin or locking bar 7 swings during the period of

shifting from one position to another, as will be hereinafter described. The base 8 of the body portion 5 is provided at its outer free end with a transverse slot 9 having communication with the first named passage-way or slot 6 and designed to co-act with said passage-way in the accommodation of the locking bar or bodkin 7.

The vertical side walls 10 of the body portion 5 are provided adjacent the outer or free ends with a pair of transversely aligned notches 11 which serve as bearings for the opposed fingers or pintles 12 formed integrally with the upper end of the bar or bodkin 7. This structure prevents removal of the locking bar from the body portion 5 and provides for the swinging of the bar at a definite point. The other end of the locking bar 7 is provided with an enlarged head 13 which co-acts with the aforementioned pintles 12 to positively retain the bar against removal. By reference to Figure 2 it will be seen that the formation of the slot 9 in the lower wall 8 of the body portion results in the provision of a shoulder or stop 14 which co-acts with another stop or shoulder 15 which is provided at the upper outer side of the transversely aligned notches 11. These stops or shoulders 14 and 15 are relatively off-set horizontally a distance substantially equal to the thickness of the locking bar or bodkin 7, so that when the several parts are arranged in locked position, said bar will be substantially in parallel relation with respect to the badge B, this idea being illustrated in Figure 1 of the drawings.

In order to retain the locking bar or bodkin 7 in locked position and in snug engagement with the two stops or shoulders 14 and 15, I pivotally mount within the channeled body 5 a pawl 16 upon a transverse pin 17 as shown in Figures 2 and 4. This pawl 16 includes a biting tooth or jaw 18 which is spaced slightly above the upper stop or shoulder 15 and is adapted to snugly contact with the face of the bar adjacent the badge B.

In attaching a badge to an article of wearing apparel, the badge being provided with a fastener of the character herein described, the locking bar or bodkin 7 is positioned as illustrated in Figure 2, this position permitting its use as threading device by means of which the fastener body 5 is guided into a button hole or the like wherein

it is to be held. Upon completion of this step the bar is swung on the pintle 12 to the full line position shown in Figure 2, at which point the actual locking operation is started. The bar is moved in substantially parallel relation with respect to the badge B the result being that the pawl 16 is slightly turned on its pivot pin 17 and since the structure is such that the extent of turning of this pawl would not permit free passage of the bar over the jaw or tooth 18, the neck 19 which connects the jaw and pawl is designed to yield slightly. This yielding obviously provides for the exertion of considerable pressure upon the locking bar 7 by the jaw or tooth 18, with the result that the bar is snugly gripped at three longitudinally spaced points. It is quite apparent that accidental movement or unlocking of 20 the device is practically impossible.

Manifestly, the construction shown is capable of certain modification and such modification as may fall within the scope of my claims, I consider within the spirit of my 25 invention.

I claim:

1. In a fastener for badges or the like, a body portion arranged upon the back of the badge and having a pair of relatively 30 off-set shoulders and an opening between the shoulders, a locking bar slidable between the shoulders, a pivoted pawl carried by the body, and a jaw on the pawl to frictionally engage the locking bar and co-act with the 35 shoulders to hold it against movement.

2. In a fastener for badges or the like, a body portion arranged upon the back of the badge and having a pair of inter-communicating

slots in its bottom wall and outer end wall to form spaced shoulders, a pivoted pawl arranged upon the body inwardly from the shoulders, and a locking bar slidable through the slots and adapted to frictionally engage the shoulders and pawl at relatively staggered points. 40 45

3. In a fastener for badges or the like, a body portion arranged upon the back of the badge and having a pair of inter-communicating slots in its bottom wall and outer end wall to form spaced shoulders, a pivoted pawl arranged upon the body inwardly from the shoulders, said body having a pair of transversely alined notches between the pawl and said shoulders, a locking bar slidable through the slots and frictionally engageable 50 55 with the pawl and shoulders, and pintles carried by the bar and adapted to be positioned in said notches at certain times.

4. In a fastener for badges or the like, a body portion arranged upon the back of the badge and having a pair of inter-communicating slots in its bottom wall and outer end wall, to form spaced shoulders, said body having a channel communicating with the slots, a pivoted pawl arranged in said channel inwardly from the shoulders, said body having a pair of transversely alined notches between the pawl and said shoulders, a locking bar slidable through the slots and frictionally engageable with the pawl and shoulders, and pintles carried by the bar and adapted to be positioned in said notches at 60 65 70 certain times.

In testimony whereof I affix my signature.

MORRIS FOLKMAN.
